UNITED STATES PATENT OFFICE.

EDWARD R. INMAN, OF FRANKLIN, PENNSYLVANIA, ASSIGNOR TO
PRODUCERS SUPPLY COMPANY, OF FRANKLIN, PENNSYLVANIA,
A CORPORATION OF PENNSYLVANIA.

COMBINED GOVERNOR AND SAFETY DEVICE FOR GAS-ENGINES.

No. 833,393.

Specification of Letters Patent.

Patented Oct. 16, 1906.

Application filed January 18, 1905. Renewed September 13, 1906. Serial No. 334,458.

To all whom it may concern:

Be it known that I, EDWARD R. INMAN, a citizen of the United States, residing at Franklin, in the county of Venango and State of Pennsylvania, have invented certain new and useful Improvements in a Combined Governor and Safety Device for Gas-Engines, of which the following is a specification, reference being had therein to the accompanying drawings.

My invention relates to an improved combined governor and safety device for explosive-engines, which will be fully understood from the following specification, reference being had to the accompanying drawings, which form a part hereof, and in which—

Figure 1 is a side elevation of a gas-engine cylinder, showing my governor in position thereon, together with the actuating mechanism. Fig. 2 is a plan view of the cylinder, one side being in section, and showing also the valve-case of my governor in section.

The object of my invention is to provide a safety or relief valve for two-cycle engines which will provide a relief for the force of an explosion in the pump-chamber when fire strikes back into said chamber from the explosion-chamber of the cylinder.

A further object of my invention is to provide, through the same means and mechanism by which my said first object is attained, a governor which will regulate the speed of the engine.

The construction of the mechanism by which I accomplish these objects is substantially as follows:

Upon the side of the cylinder 1 of a gas-engine is placed a valve-case 2, in the chamber 2' of which is seated a valve 3 of the puppet type. The valve-chamber 2' at one side of the valve 3 is open to the pump-chamber 4 of the cylinder 1 by means of the passage 2'', and the chamber upon the other side of said valve is open to the atmosphere by means of the port 5. By this arrangement, it will be understood, pressure in the pump-chamber 4 will tend to unseat the valve 3, and would do so were this not prevented by the spring 6, which bears against the valve with sufficient pressure to keep it to its seat against any normal compression in the pump-chamber; but when an explosion occurs in said cham-

ber and an abnormal pressure is thus developed therein the valve 3 is raised from its seat, and the force of the explosion is thus relieved through the port 5, and the force which would otherwise damage the engine is thus relieved without any damage whatever.

The operation of the governor is as follows: The stem 7 of the valve 3 projects through the case 2 and is provided with a knuckle 8, which is rigidly affixed to said stem. In said knuckle 8 is hinged a latch-block 9, having a longitudinal hole therein, into which one end of an eccentric-rod 10 reciprocates. The other end of rod 10 is attached to an eccentric which is secured to the crank-shaft of the engine, so that said rod reciprocates continuously when the engine is in operation. A bracket 11 is rigidly affixed to the eccentric-rod, and in said bracket a pick-blade 12 is mounted in such a manner as to be free to oscillate vertically, and the weight 13 normally holds blade 12 from engagement with the latch-block 9. When the speed of the engine exceeds a certain limit, however, the inertia of weight 13 causes it to lag, and blade 12 is thrown down into engagement with the notch 14 in the latch-block 9, valve 3 is opened, and the power charge may escape from the pump-chamber to the atmosphere instead of passing back into the explosion-chamber 15 of the cylinder.

So far as the operation of my device is concerned it is immaterial by what means the fuel charge is admitted to the pump-cylinder; but I have here shown a mixer-valve 16, through which the fuel mixture is supplied to the pump-chamber.

The piston 17 is of course operable in the cylinder, and the fuel charge passes from the pump-chamber 4 to the explosion-chamber 15 through the by-pass 18 when the piston is in the position shown, the expanded charge having previously passed out through the exhaust-port 19.

Having thus described my invention, what I claim as new, and desire to secure by Letters Patent, is—

In a combined governor and safety device for two-cycle gas-engines, the combination of an engine piston and cylinder, a crank or pump chamber having a charge-inlet, a passage leading from said chamber to the cylin-

der or explosion-chamber, and a passage to the atmosphere, an outwardly-opening valve in said passage spring-held against charge compression, but capable of yielding to the pressure of an explosion in said crank or pump-chamber, and an engine-actuated governor constructed to open said valve on excess speed.

In testimony whereof I affix my signature in presence of two witnesses.

EDWARD R. INMAN.
